United States Patent Office

Des. 204,112
Patented Mar. 15, 1966

204,112

ELECTRONIC OVEN

Donald W. Grasmehr, Edison, Ohio, assignor to The Tappan Company, Mansfield, Ohio, a corporation of Ohio

Filed Mar. 30, 1965, Ser. No. 84,510

Term of patent 14 years

(Cl. D81—10)

FIG. 1

FIG. 6

FIG. 2

FIG. 3

FIG. 4

FIG. 5

FIG. 1 is a perspective view of an electronic oven embodying my new design;

FIG. 2 is a side elevation thereof as viewed from the right of FIG. 1;

FIG. 3 is a front elevation of the FIG. 1 oven;

FIG. 4 is a side elevation thereof as viewed from the left in FIGS. 1 and 3;

FIG. 5 is a rear elevation of the oven; and

FIG. 6 is a top plan view of the oven.

The bottom of the oven, not shown, is conventionally plain.

I claim:

The ornamental design for an electronic oven, as shown and described.
